Primary Examiner — Barbara Fox*Assistant Examiner* — Mary Shannon Malley(74) *Attorney, Agent, or Firm* — Clause Eight IPS;
Michael Catania(57) **CLAIM**

The ornamental design for an intradermal biosensor, as shown and described.

DESCRIPTION

FIG. 1 is a top plan view of an intradermal biosensor, showing our new design;

FIG. 2 is a bottom plan view thereof;

FIG. 3 is a front elevation view thereof;

FIG. 4 is a rear elevation view thereof;

FIG. 5 is a side elevation view thereof;

FIG. 6 is a side elevation view thereof;

FIG. 7 is an exploded view thereof; and,

FIG. 8 is a perspective view showing the intradermal biosensor worn by a user.

The broken lines showing a human figure and the internal components of an intradermal biosensor are for the purpose of depicting environmental subject matter that forms no part of the claimed design.

1 Claim, 4 Drawing Sheets(56)
